[57] CLAIM

The ornamental design for an combined emergency flashlight and smoke alarm system, as shown and described.

DESCRIPTION

FIG. 1 is a front elevational view of the combined emergency flashlight and smoke alarm showing my new design.

FIG. 2 is a side elevational view thereof, the opposite side being a mirror image;

FIG. 3 is a top plan view thereof;

FIG. 4 is a rear elevational view thereof;

FIG. 5 is a bottom plan view thereof;

FIG. 6 is a top, front perspective view thereof;

The strap on the flashlight is fragmentarily shown in FIGS. 1, 4 and 6 and omitted from FIG. 5 for convenience of illustration.
